UNITED STATES PATENT OFFICE.

THORVALD O. QUIST, OF NEW YORK, N. Y., ASSIGNOR TO THE NATIONAL MACHINE COMPANY, OF MAMARONECK, NEW YORK, A CORPORATION OF NEW YORK.

BUTTON-SEWING MACHINE.

SPECIFICATION forming part of Letters Patent No. 783,073, dated February 21, 1905.
Application filed November 25, 1903. Serial No. 182,590.

To all whom it may concern:

Be it known that I, THORVALD O. QUIST, a citizen of the United States of America, and a resident of New York city, borough of Brooklyn, county of Kings, State of New York, have invented certain new and useful Improvements in Button-Sewing Machines, of which the following is a specification, reference being had to the accompanying drawings, forming a part thereof.

My invention relates to improvements in button-sewing machines, and particularly to means employed for locating the position of buttons with respect to the goods upon which they are to be sewed.

In sewing on buttons it has been customary heretofore to mark the places upon the goods upon which they are to be sewed, such marks registering with buttonholes with which the buttons when in position are adapted to engage. This marking takes time, and, further, the marks are sometimes wrongly placed, and, again, the buttons are sometimes sewed onto the goods in positions out of register with such marks.

In my present invention I have so arranged that that portion of the goods containing the buttonholes may be superposed upon the portion of the goods upon which it is desired to sew the buttons and have provided means for receiving the two pieces of goods so superposed beneath the button-clamp and have provided means for forcing the buttonholes open when in the sewing position, so that the buttons arranged for engagement with said buttonholes may be sewed to the goods through the open buttonholes.

The result of my invention is to cause the buttons and buttonholes to always correctly register and to avoid the expenditure of time formerly employed.

A further result of my invention is to deliver the goods in a "buttoned-up" condition without further operation. Heretofore it has been necessary to expend time in buttoning up the goods by hand when it has been desired to deliver the goods in such condition.

To accomplish the foregoing, I provide a button-sewing machine with an expanding device

comprising two relatively movable claws located immediately beneath the button-clamp. These claws are adapted to engage or hook over the sides of a buttonhole, so that when moved apart they will force the sides of the buttonhole open to expose the material beneath same. A button inserted into and held by the button-clamp may then be sewed to the material beneath the buttonhole, the stitches for sewing same passing freely between the sides of the said buttonhole.

My invention further consists in certain novel details of construction and combination of parts, as will hereinafter more fully appear.

I will now proceed to describe mechanism embodying my invention and will then point out the novel features in claims.

In the drawings, Figure 1 is a view in side elevation of a button-sewing machine including mechanism embodying my invention. Fig. 2 is an end view of same. Fig. 3 is a partial end view and a view partially in vertical section through the button-clamp and button-hole-expanding device. Fig. 4 is a detail top view, on a somewhat-enlarged scale, of certain portions of the machine, showing the button-hole-expanding device in operation, certain parts being broken away in order to illustrate better the various features of construction and operation.

In the drawings I have shown a conventional form of button-sewing machine comprising the usual bed-plate 1, overhanging arm 2, and front head 3. Stitching mechanism is represented by the needle-bar 4, carrying a needle 5 and looping or shuttle mechanism 6.

7 designates a combined work-support and button-clamp as a whole. This work-support and button-clamp comprises a carrier 8, a plate 9, an overhanging arm 10, pivoted to the carrier at 11, and a button-clamp 12. Necessary movements are imparted to the carrier 8, and hence to the parts supported thereby, for shifting the work-support and button-clamp for presenting the button and material to which it is to be sewed in the proper stitching positions. The particular mechanism for imparting these movements is not illustrated in detail herein, being well known in the art.

and forming no part of the present invention. The plate 9 is secured to the carrier 8 and forms a support for the material operated upon. The button-clamp 12 comprises an upper rigid plate 13 and a lower spring 14 and constitutes not only a button-clamp, but also a top or presser member for the work-clamp. In the drawings a button is shown in the position between the upper and lower plates of the work-clamp, such button being designated by reference character 15. The arm 10 is provided with an extension 16, to which a link, cord, or chain 17 is connected. This link, cord, or chain may connect with a treadle or other operating means whereby the arm may be rocked upon its pivotal support 11 to raise and lower the button-clamp. A spring 18 operates to move the parts in opposition to pressure applied through the link, cord, or chain 17.

20 An expanding device is arranged beneath the spring-plate 14 of the button-clamp 12, such expanding device comprising two relatively movable claws. In the present embodiment of my invention I have shown one of the claws, 19, as stationary with respect to the button-clamp. The other claw, 20, is secured to a sliding plate 21, mounted to slide in guides upon the upper plate 13 of the button-clamp 12 and spring-actuated, by means of a tension-spring 22, in one direction. A bell-crank lever 23, fulcrumed at 24 upon a support 25, secured to the button-clamp plate 13, has one of its arms in engagement with the said slide-plate 21 and is arranged with its other arm in proximity to and adapted to be engaged by an abutment 26 upon the head 3 of the machine. When the button-clamp 12 is lifted, the upper arm of the said bell-crank lever 23 will be engaged by the abutment 26, so that the said bell-crank lever will be rocked upon its support and will thereby move the plate 21 forward or in a direction toward the line of movement of the needle. The effect of this movement will be to move the movable claw 20 into line with the stationary claw 19. The parts are shown in these positions in Fig. 2 of the drawings. When the work-clamp is lowered, the bell-crank lever will be disengaged from the said abutment 26 and the spring 22 will be permitted to draw the plate 21 backward. The result of this will be to move the movable claw 20 away from the stationary claw 19, as shown in Figs. 3 and 4 of the drawings.

55 In operation material in which buttonholes have already been made is superposed upon material to which it is desired to attach buttons. The link 17 is then depressed, lifting the arm 10 and the work-clamp 12, so as to leave a space between the lower side of the button-clamp and the upper surface of the plate 9. The materials superposed as above stated are then placed between the plate 9 and the button-clamp 12 with a buttonhole longitudinally in line with the downwardly-pro-

jecting portions of the claws 19 and 20, and then slightly lifted, so as to cause the said claws to engage the sides of the buttonhole. Tension upon the link 17 is now released, permitting the arm 10 and button-clamp to descend, clamping the work between the button-clamp and the plate 9 and at the same time moving the claws 19 and 20 apart in the manner above stated. A button being now inserted between the plates 13 and 14 of the button-clamp, the button may be sewed to the lower of the two materials, the stitches passing freely between the sides of the buttonhole thus held apart. Figs. 3 and 4 show the parts after the button-clamp has descended and the expanding device has opened the buttonhole ready for a sewing operation.

What I claim is—

1. In a button-sewing machine, the combination with means for supporting a fabric to which a button is to be sewed and a fabric containing a buttonhole, of a buttonhole-expander for expanding said buttonhole, a button-clamp, and means for sewing a button supported by said clamp through the buttonhole so expanded to the fabric supported beneath same.

2. In a button-sewing machine, the combination with button-stitching mechanism including means for producing relative lateral movements between the needle and button, means for supporting fabric to which a button is to be sewed and fabric containing a buttonhole, and a button-clamp, of a button-hole-expander arranged to expand a buttonhole beyond the limits of the said lateral movements, thereby permitting stitching of the button through the open buttonhole.

3. In a button-sewing machine the combination with button-stitching mechanism, and a button-clamp, of a buttonhole-expander located beneath the button-clamp.

4. In a button-sewing machine, the combination with button-stitching mechanism including means for producing relative lateral movements between the needle and a button, of a buttonhole-expanding device comprising two claws movable with respect to each other and adapted to engage the walls of a button-hole-slit, and in their movements to expand the buttonhole beyond the limits of the said relative lateral movements between the needle and the button, whereby operation of sewing the button may be conducted between the walls of the open buttonhole to fabric supported beneath same, and means for operating the said expanding device.

5. In a button-sewing machine the combination with button-stitching mechanism, and a button-clamp, of a buttonhole-expander comprising two relatively movable claws located beneath the button-clamp.

6. In a button-sewing machine the combination with button-stitching mechanism, and a button-clamp, of a buttonhole-expander com-

- prising two relatively movable claws located beneath the button-clamp and carried thereby.
7. In a button-sewing machine the combination with button-stitching mechanism and a 5 combined work-support and button-clamp, of a buttonhole-expander located between the work-support and the button-clamp.
8. In a button-sewing machine the combination with button-stitching mechanism, of a 10 combined work-support and button-clamp, the button-clamp movable with respect to the work-support but carried thereby, and a buttonhole-expander carried by the button-clamp and located between the button-clamp and the 15 work-support.
9. In a button-sewing machine the combination with button-stitching mechanism, of a button-clamp, a buttonhole-expander carried thereby, and means for raising and lowering 20 the button-clamp and simultaneously operating the buttonhole-expander.
10. In a button-sewing machine the combination with button-stitching mechanism and a work-support, of a buttonhole-expander comprising 25 two relatively movable claws, means for raising and lowering the buttonhole-expander, and means simultaneously operated for operating the said relatively movable claws.
11. In a button-sewing machine the combination with button-stitching mechanism, of a 30 work-support, a button-clamp, a buttonhole-expander comprising two relatively movable claws carried by the button-clamp and located between the said button-clamp and the work-support, means for raising and lowering the 35 work-clamp with respect to the work-support, and means simultaneously operated for opening and closing said claws.
12. In a button-sewing machine the combination with button-stitching mechanism, of a 40 combined work-support and button-clamp secured together but relatively movable with respect to each other, a buttonhole-expander comprising two relatively movable claws carried by the button-clamp, means for moving 45 the button-clamp with respect to the work-support, an operating-lever for the button-hole-expander, and means engaging the operating-lever to move same upon movements of the button-clamp with respect to the work- 50 support.
